CLAIM

The ornamental design for a mirror, as shown and described.

DESCRIPTION

FIG. 1 is a front-side perspective view of a mirror according to an embodiment of the invention. The view from the other front side being a mirror image thereof.

FIG. 2 is a front elevational view of a mirror according to an embodiment of the invention.

FIG. 3 is a side elevational view of a mirror according to an embodiment of the invention. The view from the opposite side being a mirror image thereof; and,

FIG. 4 is a top plan view of a mirror according to an embodiment of the invention.

The back side of the mirror is not shown and forms no part of the claimed invention.

1 Claim, 2 Drawing Sheets
